United States Patent Office

Des. 224,849

Patented Sept. 26, 1972

224,849

PORTABLE CARRYING CASE FOR PHOTOGRAPHIC I.D. EQUIPMENT

James M. Conner, Westchester, N.Y., assignor to Polaroid Corporation, Cambridge, Mass.

Filed June 17, 1971, Ser. No. 154,257

Term of patent 14 years

Int. Cl. D3—02

U.S. Cl. D87—1

FIG. I.

FIG. 2.

FIG. 3

FIG. 1 is a front and left end perspective view of a portable carrying case for photographic I.D. equipment showing my new design;

FIG. 2 is a rear and left end perspective view, the right end being identical thereto;

FIG. 3 is a bottom plan view thereof.

I claim:

The ornamental design for a portable carrying case for photographic I.D. equipment, as shown and described.
